UNITED STATES PATENT OFFICE.

FRANZ A. FULLER, OF NEWARK, NEW JERSEY.

SAFETY RAZOR.

1,205,187

Specification of Letters Patent. Patented Nov. 21, 1916.

Application filed March 19, 1915. Serial No. 15,461.

To all whom it may concern:

Be it known that I, FRANZ A. FULLER, a citizen of the United States, residing in the city of Newark, in the county of Essex and State of New Jersey, have invented certain new and useful Improvements in Safety Razors, of which the following is a full, clear, and exact description, such as will enable others skilled in the art to which it pertains to make, construct, and use the same, reference being had to the accompanying drawings, and to numerals of reference marked thereon, forming a part of this specification.

15 My invention relates to improvements in safety razors and has for its object, the production of a safety razor having a blade guard, a pivotally supported blade holder in which the blade is pivotally supported, 20 and means for rocking the blade while in the frame for stropping one of the blade edges without removing the blade from the frame, and means for positively adjusting and holding the cutting edge of the blade in 25 shaving position relative to the guard teeth.

Another object of my invention is to provide improved means to cause a strop to rock a pivotally-supported blade holder with its pivotally supported blade in such 30 a manner as to positively prevent the blade from cutting or injuring the strop.

A further object of my invention is to provide means to limit the movement of the blade holder in one direction, so as to 35 cause a strop to rock the blade in such a manner that during the stropping operation of the blade, the edge thereof adjacent to the guard, is to come in contact with the strop only.

40 With these ends in view, my invention consists in certain novelties of construction and arrangements of parts as hereinafter set forth and pointed out in the claims.

While the preferred form of my invention is illustrated in the accompanying drawings, yet it is to be understood that minor changes may be made without departing from the scope thereof.

In the accompanying drawings, Figure 1 45 represents a side elevation of my improved device, partly broken away and partly in section, illustrating the manner in which the device is to be used for stropping the blade and illustrating the cutting edge of the blade in dotted lines in stropping relation to the strop, and in full lines in engage-

ment with the means for limiting the movement of the blade to prevent the opposite cutting edge of the blade from engaging with the strop. Figs. 2 and 3 represent respectively, rear and side elevations of the same; and Fig. 4 represents a rear view of the latch detached from the device, for locking the razor blade in its adjusted position. Similar numerals of reference refer to like parts throughout the specification and drawings.

In the drawings, 1 represents the body or frame of my improved device, which body may be stamped from sheet metal or the like; and afterward bent into the desired shape as shown. Said body or frame comprises two opposite side portions 2 and 3, parallel each to each, and connected by a central cross piece 4, from one side of which extends a portion 5 constructed to grip the blade 6 at the front corners, the sharpened edge of the blade resting upon the bent-over end of the guard 7, which is provided with the usual perforations 8, the free end of which is bent downwardly, and which is sufficiently in advance of the edge of the blade to afford the necessary protection against accidental cutting.

The forward and outer end of the guard 7 has upwardly extending stops 9, for engagement with the corners of said cutting edge of the blade 6, to prevent said cutting edge from projecting too far beyond the guard 7 to at all times maintain the cutting edge of the razor blade in the proper and adjusted position relative to the guard teeth. These stops 9 may, for convenience sake, be formed integral with the frame 1 as shown, or secured thereto in any convenient or desired manner. The frame 1 is provided with a removable handle 10, which if desired, for convenience sake in packing, may be detached from the frame.

Journalized in the ends of the frame 1 are 100 hollow rollers 11-11, rotatably mounted on a cylindrical rod or shaft 12, fixed at its ends to the respective side portions 2 and 3 of the body or frame 1, and serve as rollers to be engaged by the strop when the device 105 is to be used for stropping the blade, as illustrated in Fig. 1 of the drawings.

The pivotally supported blade holder may be stamped from sheet metal or the like, and afterward bent into the desired shape 110 as shown. Said blade holder comprises two opposite side portions 13 and 14, parallel

each to each, and connected by a rear cross piece 15. The lower ends of the two opposite side portions 13 and 14 are apertured and bent outwardly in order to embrace the 5 opposite side portions 2 and 3 of the body or frame 1, and to which the blade holder is pivotally connected in any convenient manner, as by means of pivots 16. This manner of pivotally and yieldingly connecting the blade holder support with the body or frame 1 of the device, provides positive means for preventing the cutting edge of the blade from cutting or gouging the strop during the stropping operation.

15 The top edge of the rear cross piece 15, together with the pinion or gear 20, a portion of the peripheral edge of which is stripped of teeth, provide means to limit the movement of the blade and the blade 20 holder in one direction, so as to cause but one side of the cutting edge of the razor blade to come in stropping engagement with the strop.

The forward and backward movement of 25 the pivoted blade holder is limited by the shape given to the lower portion of the side portions 13 and 14 near their outwardly bent and apertured ends, which shape corresponds with the shape of the top edges of 30 the side portions 2 and 3 of the body or frame 1, when the parts are in the position illustrated in Figs. 1 and 3 of the drawings.

The side portions 13 and 14 have upper 35 and lower holes forming bearings for the pivoted ends of an upper shaft 17 and a lower roller 18, both extending transversely of the blade holder. The upper shaft 17 and the lower roller 18 are connected by 40 means of pinions or gears 19 and 20, so that drawing the device along the strop will tend to turn the said shaft 17 and when the direction of sliding the device is reversed, the shaft 17 will be turned over according to 45 the principles already well understood in the art.

The shaft 17 carries the blade holder 21, which holder may consist of a piece of sheet metal wrapped around the shaft 17, and secured thereto in any convenient or desired manner, so as to provide resilient clamping jaws 22 and 23 to receive the razor blade 6 between themselves, as has been common in general heretofore.

55 The razor blade, as shown, is preferably made of sheet metal provided with a longitudinal cutting edge, but I wish it to be understood that razor blades of peculiar construction may be employed.

60 Pivots secured to a depending lug 24, formed integral with the body or frame 1, by means of a pivot 25, is the latch plate 26, the inner side of said latch plate designed to bear upon the rear portion of the cross 65 piece 15, in order that when said latch plate

is manipulated by means of the finger piece 27 secured to the latch plate, the cutting edge of the blade 6 is brought into an adjusted operative position relative to the guard or removed therefrom.

70

The latch plate is provided with an elongated protuberance 28, designed to engage with one of a series of internal teeth 29 formed on the cross piece 15, in order to provide step-like means whereby the razor 75 blade can be locked in its adjusted position to prevent forward and rearward displacement.

The operation of the device is as follows: When the device is to be used for stropping 80 purposes, the blade holder is swung up as shown in Fig. 1 of the drawings, by disengaging the latch plate from the cross-piece of the blade holder support; the strop is then passed over the roller 11 at one end 85 of the frame 1 and under the roller 18 on the blade holder support and then out through and over the roller 11 at the other end of the frame 1 of the device, as clearly indicated in Fig. 1 of the drawings.

90

The attaching end of the strop (not shown) is hooked over any suitable support, while its opposite end (likewise not shown) is held in one hand. The other hand grips the handle 10 of the device, and reciprocates 95 said device back and forth along the strop, thereby permitting the edge of the blade adjacent to the guard only to be engaged with the strop.

The present invention provides a very 100 efficient and exceedingly simple safety razor, the same being constructed of a minimum number of parts, which are of such shape as to lend themselves readily to manufacture by the use of suitable punches and dies from 105 ordinary sheet metal, and which parts are reduced to the simplest operative efficiency; and further, the invention provides a safety razor in which the accidental cutting or injuring of the strop by the blade is prevented, and the stropping of but one side of the 110 cutting edge of the blade is possible.

The longitudinal cutting edge of a safety 115 razor blade is usually provided with two surfaces, though only one of the surfaces is used during the shaving operation, and that is the surface which lies against the guard and applied to the face when shaving. Experience has demonstrated that it is only necessary to strop that surface of the cutting edge of the blade which lies adjacent to the guard, and that by so doing, a superior 120 edge is produced.

I claim:

1. A safety razor comprising a frame 125 adapted to slide longitudinally of a strop, a roller at each end of said frame, a blade holder support pivotally connected to said frame intermediate of said rollers, a roller in said blade holder support, a blade holder 130.

- 5 pivotally connected to said blade holder support, means carried by said blade holder support for transmitting rotary movement to said blade holder from said roller and means located on the frame for adjusting the blade relative to the frame.
- 10 2. A safety razor comprising a frame having guard teeth at one edge and a handle extending from the frame, a blade holder support pivotally connected to said frame, a blade holder pivotally connected to said blade holder support, a blade located in said blade holder and means to limit the forward and rearward movement of the pivotally connected blade holder support.
- 15 3. A safety razor comprising a frame having guard teeth at one edge and a handle extending from the frame, a blade holder support pivotally connected to said frame, a blade holder pivotally connected to said blade holder support, a blade located in said blade holder and means to limit the movement of the blade holder in one direction so that stropping of but one side of blade is possible.
- 20 4. A safety razor comprising a frame adapted to slide longitudinally of a strop, a roller at each end of said frame, a blade holder support pivotally connected to said frame intermediate of said rollers, a roller in said blade holder support, a blade holder pivotally connected to said blade holder sup-
- 25 port, means carried by said blade holder support for transmitting rotary movement to said blade holder from said roller and means to limit the movement of the blade holder in one direction so that stropping of but one side of blade is possible.
- 30 5. A safety razor comprising a frame adapted to slide longitudinally of a strop, a handle extending from the frame, a blade holder pivotally connected to said frame, means for transmitting rotary motion to said blade holder, a blade located in said blade holder and means to limit the movement of the blade holder in one direction, thereby permitting only that surface of the cutting edge of the blade which lies adjacent the guard to be stropped.
- 35 6. A safety razor comprising a frame adapted to slide longitudinally of a strop, a blade holder pivotally supported in said frame, means for transmitting rotary movement to said blade holder and means to limit the movement of the blade holder in one direction, thereby permitting only that surface of the cutting edge of the blade which lies adjacent the guard to be stropped.

This specification signed and witnessed this 17th day of March, 1915.

FRANZ A. FULLER.
